UNITED STATES PATENT OFFICE.

JOHN F. COTTER, OF KANSAS CITY, MISSOURI.

DESIGN FOR A CLOSET-BOWL.

SPECIFICATION forming part of Design No. 32,967, dated July 17, 1900.

Application filed May 12, 1900. Serial No. 16,518. Term of patent 14 years.

To all whom it may concern:

Be it known that I, JOHN F. COTTER, a citizen of the United States, residing at Kansas City, in the county of Jackson and State of Missouri, have invented and produced a new and original Design for a Closet-Bowl, of which the following is a specification, reference being had to the accompanying drawings, forming a part thereof.

Figure 1 is a perspective view. Fig. 2 is a section on the line xx .

As shown in the drawings, the leading feature of my design is a bowl having a lateral projection at the side thereof, which is continued in an upwardly and forwardly direction, as at B. The bowl contracts from above

downward, as shown in Fig. 2, and inward, as shown in Fig. 1.

D is an opening or channel.

Having fully described my invention, what I claim as new, and desire to secure by Letters Patent, is—

The design for a closet-bowl, as herein shown and described.

In testimony whereof I have signed my name to this specification in the presence of two subscribing witnesses.

JOHN F. COTTER.
